UNITED STATES PATENT OFFICE.

JOSEPH SCHERMULY, OF WICHITA, KANSAS.

OIL BURNER.

Application filed June 19, 1923. Serial No. 646,343.

To all whom it may concern:

Be it known that I, JOSEPH SCHERMULY, a citizen of the United States, resident of Wichita, county of Sedgwick, and State of Kansas, have invented certain new and useful Improvements in Oil Burners, reference being had to the accompanying drawings, consisting of two sheets, which form a part of this application.

10 My invention relates to a hydrocarbon oil burner.

The object of my invention is to provide a burner equally distributing the oil uniformly at the periphery of a disk dispensing member.

15 A further object of my invention is to provide means for heating and circulating the air, which comes in contact with the oil as it is dispensed at the combustion point.

20 A still further object of my invention is to provide simple means for disposing of the overflow of superfluous oil.

Referring to the drawings Fig. 1 is a top view of the burner with parts removed showing the different members. Fig. 2 is a side view partly in section for convenience of illustration. Fig. 3 is an inverted view of the air chamber, showing the circulating system. Fig. 4 is a bottom view of the bottom member of the burner.

30 1 is the base member functioning as a reservoir on which is mounted a member 2 said member having an outside wall A and an inside wall B the said walls being connected at the top by an annular curved member C, said curved member having a lip D elevated sufficient to hold a small quantity of fuel oil. 4 is an annular depression adapted to receive the overflow of oil as it passes over lip 40 D, and said oil being conveyed from said depression through a pipe 5.

The said members 1 and 2 are fastened together by means of corresponding ears 6, a plurality of which are stationed around the periphery of members 1 and 2, said ears having holes registering and thro which passes bolts binding said members tightly together.

50 7 is a convex member having grooves 8, radiating as shown in Figure 1. The said convex member has a plurality of standards 8¹ integral with said disk and adapted to rest on lip D and the lower end of said standards being shaped to conform to the shape of lip D by which means the said

disc is held concentric to the opening 9 which is formed by lip D.

10 is a pipe which is screwed into a hub 11 of the said disc 7 functioning as a feed pipe dispensing the oil in the grooves 8 and from 60 thence to the periphery of said disk 7 at which place the oil and heated air herein-after described will mix for combustion; the said disc being supported by standards 8¹ resting on lip D, is held firmly thereto by 65 means of a union 12 being threaded on pipe 10 and contacting on base member 1 at 13, and the said union functions as a connection for pipe 10 and pipe 14 which connects with a fuel oil tank, not shown.

70 15 is a hood concave to conform to the convex surface of disc 7 by which means the oil is confined to travel thro the grooves 8 making an equal distribution of the oil about the periphery of said disc as heretofore described and the said hood 15 being larger in diameter, functions as protection for the escaping oil, causing the said oil and hot air to contact within the heating chamber, formed by the said discs and the gases 80 formed will pass thro the opening 16 said opening being between the periphery of disc 15 and the curvature of wall C at which point combustion takes place.

85 In base member 1 is an opening 17 functioning as an air inlet, said opening being positioned between the walls A and B as shown by dotted lines E in Fig. 3.

90 When the burner is in action the curved wall C is heated and the heat being transmitted into air chamber 3 creates a circulation of the hot air flowing in the direction indicated by the arrows as shown in Fig. 3 and discharging thro the opening 9 under discs 7 and hood 15 preheating the oil that is flowing 95 between said disc as heretofore described, and when said oil and hot air contacts, a combustion gas is formed, and the mechanism as constructed, constitutes my oil burner.

100 Such modifications may be made as come within the scope of the appending claim.

Having thus described my invention what I claim as new and desire to secure by Letters Patent is:—

105 In an oil burner, a feed pipe having an overflow reservoir mounted thereon, an overflow pipe for said reservoir, an air inlet in the rim of said reservoir, a generating pan and circulating air chamber combined 110

mounted on said reservoir rim, and the air chamber registering with the opening in the said rim, means for fastening the rim of said reservoir to the outside wall of the air circulating chamber, a convex member mounted on the supply pipe, said member having a plurality of radiating grooves in the convex face thereof, and on the opposite side of said member a plurality of legs adapted to seat

on the rim of said generating pan, a hood 10 mounted on the convex member so that the oil will be distributed uniformly through the radiating grooves, and also to function as a heating element to generate the oil into gas, all for the purpose set forth and de- 15 scribed.

JOSEPH SCHERMULY.
